(57) **CLAIM**

I claim the ornamental design for roof vent with fan, as shown and described.

DESCRIPTION

FIG. 1 is a top perspective view of a roof vent with fan; FIG. 2 is a top view thereof; FIG. 3 is a top view thereof, shown without the upper screen; FIG. 4 is a bottom view of the roof vent with fan of FIG. 1; FIG. 5 is a bottom view thereof, shown without the lower screen; and,

FIG. 6 is a left side view of the roof vent with fan of FIG. 1, the right side, front side, and back side being the same. The broken lines in the drawings depict portions of the roof vent with fan that form no part of the claim.
